US00D702615S

(12) **United States Design Patent**
Conway et al.

(10) **Patent No.:** **US D702,615 S**
(45) **Date of Patent:** **** Apr. 15, 2014**

(54) **GRILLE CROWN**

(71) Applicants: **Scott M. Conway**, Flower Mound, TX (US); **Derek Sancer**, Corinth, TX (US); **Sodarith Sibounheuang**, Lewisville, TX (US); **William J. Johnson**, Dallas, TX (US)

(72) Inventors: **Scott M. Conway**, Flower Mound, TX (US); **Derek Sancer**, Corinth, TX (US); **Sodarith Sibounheuang**, Lewisville, TX (US); **William J. Johnson**, Dallas, TX (US)

(73) Assignee: **PACCAR Inc**, Bellevue, WA (US)

(**) Term: **14 Years**

(21) Appl. No.: **29/447,870**

(22) Filed: **Mar. 7, 2013**

(51) **LOC (10) Cl.** **12-16**

(52) **U.S. Cl.**

USPC **D12/216**

(57) **CLAIM**

The ornamental design for a grille crown, as shown and described.

DESCRIPTION

FIG. 1 is a perspective view of a grille crown according to our new design;

FIG. 2 is a front view of the grille crown of FIG. 1;
FIG. 3 is a top view of the grille crown of FIG. 1; and,
FIG. 4 is a side view of the grille crown taken from the left side of FIG. 1, the side view taken from the side opposite of FIG. 4 being mirror symmetrical thereto.

The rear of the grille crown is unornamented.

1 Claim, 3 Drawing Sheets
